UNITED STATES PATENT OFFICE.

WILLIAM LEONHARDT, OF BALTIMORE, MARYLAND, ASSIGNOR TO
LEONHARDT WAGON MANUFACTURING COMPANY, OF BALTI-
MORE, MARYLAND, A FIRM.

DUMPING COAL-WAGON.

No. 810,953.

Specification of Letters Patent.

Patented Jan. 30, 1906.

Application filed June 24, 1905. Serial No. 266,761.

To all whom it may concern:

Be it known that I, WILLIAM LEONHARDT, of the city of Baltimore and State of Maryland, have invented certain Improvements 5 in Dumping Coal-Wagons, of which the following is a specification.

This invention relates to certain improvements in the spout to which the discharge-chute is connected; and it consists in a peculiar 10 construction of the said spout whereby the same may be extended in length and deflected to either side of the longitudinal center line of the wagon-body in order that the wagon in discharging its load may be placed in other positions than one directly in alignment with the place to which the coal is to be deposited, as will hereinafter fully appear.

In the further description of the said invention which follows reference is made to 20 the accompanying drawings, forming a part hereof, and in which—

Figure 1 is a top view of the rear end of a dumping coal-wagon provided with the improved spout and showing the spout as placed in a central position. Fig. 2 is a similar view, 25 except that the spout is shown as elongated and deflected to the left. Fig. 3 is a front view of Fig. 1. Fig. 4 is a side view of the spout as shown in Fig. 2 and looking in the 30 direction indicated by the arrow in that figure. Fig. 5 is a perspective view of a part of the spout.

Referring now to the drawings, 1 is the back end of the wagon-body, and 1^a the rear 35 wall of the same. The bottom of the body is denoted by 1^b, and beneath it is secured the bar 2, which sustains the horizontal base-plate 3, forming a part of the improved spout. The outer portion of the base-plate 3 is 40 flanged to form the vertical walls 3^a, which are strengthened by the strap 4. The plate 3 when not held by extraneous devices may be moved forward or backward or swung around to either side of the longitudinal center line of the wagon-body. In Fig. 1 it is 45 shown in dotted delineation as extended without deflection to either side and in Fig. 2 as both extended and turned to the left. A

reversed deflection is illustrated by the dotted lines.

The rear wall 1^a of the body 1 is provided with the usual delivery-opening 5, having at its sides the guide-bars 7, between which and the outer surfaces of the wall the gate 9 is adapted to slide vertically.

To the bars 7 are hinged the side plates 10 of the spout, which are situated within the side walls or flanges of the base-plate 3, with their lower edges in contact with the base-plate proper, and at the end of each of the 60 side plates is formed a lip 12, with which the horizontal portion of the strap 4 comes in contact to limit the outward movement of the base-plate, as shown in Fig. 4. The strap 4 will engage both lips when it is drawn out 65 in a straight line; but should the base-plate in its extension be thrown to one side only one lip will act as a stop, as shown in Fig. 2.

13 13 are hooks hinged to the rear wall of the wagon-body, adapted to hook into eyes 70 15, projecting from the side walls or flanges of the base-plate.

When the spout is not in use, the base-plate is pushed back and hooked at both 75 sides, as shown in Fig. 1; but when in use and deflected to one side one of the hooks is disengaged from its eye, as shown in Fig. 2.

It will be understood that with the extensible base-plate having the side walls on flanges, as shown and described, in connection with the hinged side plates a longer inclined surface against which the discharged coal will strike is produced than when the spout is devoid of extensibility and is adapted for deflection only, and the increased 85 length of the inclined surface effected as described is a decided advantage in that two different angles are produced in the discharge apparatus instead of one, which gives a more gradual change in direction taken by the 90 moving coal, as shown in Fig. 2.

17 (see Fig. 3) is the chute pivoted to the tray 19, as is common in wagons of this class.

I claim as my invention—

In combination with the body of a wagon 95 having a delivery-opening, a spout which

consists of a flanged plate situated under the body of the wagon and susceptible of an endwise movement, and of lateral deflection, a pair of plates hinged to the wagon-body with their free ends within the space formed by the separated flanges of the first plate, a stop to limit the endwise movement of the flanged plate, and fastenings whereby the said

flanged plate may be held in a straight or a laterally-deflected position, substantially as to specified.

WILLIAM LEONHARDT.
